ELECTRIC CIRCUIT BREAKER OF THE
GAS-BLAST TYPE

Donald Foster Amer, Newcastle-on-Tyne, England

Application September 29, 1942, Serial No. 460,162
In Great Britain April 15, 1940

10 Claims. (Cl. 200—148)

This application is a continuation-in-part of the present applicant's copending United States of America application Serial No. 388,700, now Patent No. 2,302,592, granted November 17, 1942.

The invention relates to an electric circuit-breaker of the kind in which a blast of deionising gas is caused to flow through a nozzle or vent to assist in extinguishing the arc. In such circuit-breakers the arc is usually drawn out by relative movement of the arcing contacts of the circuit-breaker, but for efficient operation it is desirable for the nozzle to be of relatively small size and this gives rise to difficulty in cases where the normal current-carrying capacity required involves comparatively large contact surfaces.

The present invention has for its object to avoid this difficulty and at the same time to afford increased speed and certainty of operation.

The circuit-breaker according to the invention comprises arc-initiating contacts which are located on the high pressure side of the nozzle or vent and by whose separation the arc is initially formed, an arcing contact which is supported from the high pressure side of the nozzle or vent and is connected to one terminal of the circuit-breaker and to which one root of the arc is transferred by the gas-blast from the arc-initiating contacts, the arc when so transferred extending from such arcing contact towards the low pressure side of the nozzle or vent, and an auxiliary electrode located on the low pressure side of the nozzle or vent and connected through a resistance to one terminal of the circuit-breaker.

The second arcing contact to which the other root of the arc is transferred by the gas-blast may be arranged in various ways. Thus this contact may be constituted by the low pressure end of the nozzle or by a contact mounted therein and connected thereto or by a contact mounted near the nozzle or vent on the low pressure side thereof, and in such cases the auxiliary electrode may conveniently be disposed on the low pressure side of the second arcing contact and connected through the resistance to the first arcing contact.

There may however be two nozzles in axial alignment and the gas-blast may be constituted by two streams of gas flowing towards one another respectively through the two nozzles and discharging outwardly between the nozzles, each nozzle having an arcing contact supported from its high pressure side and a set of arc-initiating contacts located on its high pressure side, whilst a single auxiliary electrode is located in the low pressure zone between the nozzles and is con-

nected through the resistance to the arcing contact supported from the high pressure side of one of the nozzles.

The separating movement of the arc-initiating contacts or of each set of arc-initiating contacts may take place in a direction transverse to the length of the arc in the transferred position or in a direction substantially parallel thereto.

The invention may be carried into practice in various ways, but some convenient alternative arrangements according thereto are illustrated by way of example in the accompanying drawings in which

Figure 1 is a somewhat diagrammatic longitudinal section through one construction,

Figures 2 and 3 are longitudinal and transverse sections through a modified construction,

Figure 4 illustrates another modified construction, and

Figure 5 shows a further alternative employing two breaks in series.

In the construction of Figure 1, the circuit-breaker contacts are enclosed within an insulating casing A of generally cylindrical shape, and at a suitable point in the length of the casing is mounted a metal housing B¹ containing a nozzle B which may be of insulating material or of metal. Gas under pressure can be admitted, when required, from a suitable reservoir into one end of the casing A, whilst the other end serves for the discharge of the arc gases, the nozzle B diverging towards the discharge end.

On the high pressure side of the nozzle a rod C is mounted in axial alignment with the nozzle, the end C¹ of this rod constituting one of the fixed arcing contacts of the circuit-breaker. Surrounding this rod C and connected to it by webs D¹ is a tube D constituting the fixed arc-initiating contact, the arrangement being such that part of the gas-blast can flow between the rod C and the tube D. Although this arrangement is usually preferable, the rod and tube may, if desired, be replaced by a simple rod or tube serving both as arcing contact and as arc-initiating contact.

The moving arc-initiating contact is constituted by a bridging contact E in the form of a group of inwardly spring-pressed contact fingers engaging with the tube D and is operated by the action of the gas-pressure on a piston E¹ carried by the bridging contact. These parts may be arranged in various ways. Thus the movement of the bridging contact may take place in the transverse direction (as shown in the constructions of Figures 2 to 5) or alternatively, as in Figure 1, the movement may take place in a direction par-

allel to the nozzle axis, preferably towards the discharge end of the casing A. Thus in the construction of Figure 1 the piston E¹ slides on the inner surface B² of the metal housing B¹ under the control of the gas pressure against the action of a spring E², and the bridging contact E engages with an external surface B³ on the nozzle B and always remains in contact therewith.

Thus in the normal closed position of the circuit-breaker the bridging contact E serves to connect the tube D, which is connected to one of the circuit-breaker terminals D², with the metal housing B¹, to which the other circuit-breaker terminal B⁴ is connected, the metal housing in turn being connected to a second fixed arcing contact in the low pressure zone.

This second fixed arcing contact may be constituted by the low pressure end of the nozzle B itself, the nozzle in this case being of conducting material, or alternatively by a separate contact (indicated in dotted line at B⁵) which may be mounted in the low pressure end of the nozzle or near thereto in the discharge passage. Such separate contact B⁵ may be centrally mounted on webs in the nozzle or in a part of the metal housing beyond the nozzle, or may consist of a bar extending diametrically across the nozzle or the low pressure zone beyond it (as for example is shown in Figures 2 and 4). When such separate contact is employed the nozzle B may be of insulating material or of conducting material.

Mounted in the discharge passage at a suitable distance beyond the second fixed arcing contact is an auxiliary electrode F, which may consist (as shown) of a central electrode supported on webs F¹ in the main casting A or (as in Figures 2 and 4) of a bar extending across the casing. This auxiliary electrode F is connected by a resistance F² to the first fixed arcing contact C¹, such resistance (shown diagrammatically in the drawings) conveniently being housed in a recess in the insulating wall of the main casing A and being insulated from the metal housing B¹ and the second fixed arcing contact.

Thus in the normal closed position of the circuit-breaker the bridging contact E completes the circuit between the arcing contact tube D and the metal housing B¹ and the auxiliary electrode F performs no useful function. It will be clear that the contact surface area to suit any required normal current-carrying capacity can readily be provided by suitably arranging the bridging contact fingers without alteration of the size of the nozzle or other associated parts.

When it is desired to open the circuit-breaker, gas under pressure is admitted into the casing A, and acts on the piston E¹ to effect the separating movement of the arc-initiating contacts, the arc being drawn out in the transverse direction or parallel to the axis, as the case may be. Immediately the arc forms, the gas-blast acts on it and tends to blow it through the nozzle B, as the result of which one arc root will establish itself on the first fixed arcing contact formed by the end C¹ of the central rod C, whilst the other arc root will, if the nozzle is of conducting material, first be transferred to the high pressure end of the nozzle and will thence travel along the nozzle surface to the low pressure end thereof and will establish itself on the second fixed arcing contact. If the nozzle is of insulating material the arc will loop through the nozzle until it comes into contact with the second fixed arcing contact B⁵, whereupon part of the arc will

be immediately short-circuited. Whichever action takes place, the result will be that the arc is almost immediately transferred from the arc-initiating contacts to a position in which it extends through the nozzle B between the two fixed arcing contacts and lies substantially along the nozzle axis, the arc thus being brought into the position most favourable to arc-extinction by the gas-blast.

The auxiliary electrode F does not come into full operation until after the arc has gone out, its primary purpose being to control any restriking of the arc. Thus the gas-blast will have swept some of the ionized gases from the arc into the space between the second arcing contact and the auxiliary electrode and will thus form a possible current path between them in parallel with the arc gap between the arcing contacts, the resistance F² being in series with such current path. The parts are so dimensioned that any restriking of the arc will take place between the second arcing contact and the auxiliary electrode F, and the current in such arc will be limited by the resistance F² and will in the case of an A. C. circuit-breaker be at unity power factor, so that the arc will be readily and easily extinguished by the gas-blast.

The foregoing arrangement may be modified in various ways other than those above mentioned. Thus, if desired, the nozzle may be replaced by a simple restricted aperture in a disc, such disc being of insulating material or of conducting material connected to a separate arcing contact on the low pressure side. One such arrangement is shown in Figures 2 and 3, wherein as above mentioned a lateral arc-initiating movement is used. In this arrangement the rod, tube and bridging contact are replaced by a fixed arc-initiating contact G in the form of a number of flat spring contact fingers engaging with a moveable knife blade contact H connected to a piston H¹ acted upon by the gas-blast against the action of a spring H² to move transversely with respect to the axis of the nozzle or vent, which is in the form of a restricted aperture J in a disc J¹ mounted across the main casing A. In the example illustrated this disc J¹ is of metal and is connected to the fixed contact G, whilst the second arcing contact is in the form of a bar K, extending across the casing A on the discharge side of the aperture J in the direction of movement of the knife blade H and is likewise connected to the fixed contact G. The auxiliary electrode L is also in the form of a bar parallel to the bar K and on the discharge side thereof, and is connected through a resistance L¹ to the knife blade contact H. The operation of this arrangement will be clear from the description given above in respect of Figure 1.

Figure 4 shows another modification, in which the discharge passage is formed in a lateral branch M of the main cylindrical casing A, with the nozzle or equivalent restricted aperture J carried by a suitable insulator M¹ in such lateral branch. The arrangement of the apertured disc J¹, the arcing contact bar K and the auxiliary electrode L are generally analogous to those of Figures 2 and 3, and Figure 4 shows a convenient housing for the resistance L¹ between the insulator M¹ and the insulating wall of the lateral branch M². The resistance L¹ is connected to one of two fixed arcing tips N N¹, and the apertured disc J¹ and second arcing electrode K are connected to the other. A bridging contact member N², which can move along the main in-

sulating casing A under the action of the gas-blast, normally connects the two arcing tips together but breaks such connection when moved by the blast, so that the arc initially forms between the two arcing tips and is blown through the aperture J on to the second arcing contact K so that it extends from the arcing tip B to the second arcing contact K, the auxiliary electrode L coming into full action as above described in the event of any restriking of the arc.

In a further alternative arrangement, shown diagrammatically in Figure 5, there are two nozzles O O¹ in axial alignment, the nozzles diverging towards one another, so that the two gas streams flow towards one another through the nozzles and discharge outwardly from the low pressure zone between them. Each nozzle is provided on its high pressure side with a fixed arcing contact and with arc-initiating contacts, such contacts being arranged with respect to the nozzle in one or other of the ways above described. In the actual example illustrated, a simple rod P (or P¹) serves both as fixed arcing contact and as fixed arc-initiating contact, and the moving arc-initiating contact Q (or Q¹) moves laterally under the action of the gas-blast against spring pressure. The two moving arc-initiating contacts Q Q¹ are connected together by a connection Q², so that the two breaks are in series, the rods P P¹ being respectively connected to the circuit-breaker terminals indicated at P² P³. The arcing contacts constituted by the ends of the rods P P¹ on the high pressure sides of the nozzles cooperate with a single auxiliary electrode R in the low pressure zone, this electrode being connected to the arcing contact P¹ through a resistance R¹.

Thus when gas under pressure is introduced simultaneously at both ends, the two gas streams respectively cause the two sets of arc-initiating contacts to open and blow the arcs through the nozzles O O¹ so that they impinge on the auxiliary electrode R, thereby in effect making up a single arc extending between the two arcing contacts P P¹ through the two nozzles. Any restriking of the arc will take place between the auxiliary electrode R and that one P of the arcing contacts to which the resistance R¹ is not connected, and complete extinction of the arc will readily and quickly follow. The fact that the resistance R¹ is connected across part of the arc before the arc goes out will also assist in limiting the arc energy and thus facilitating extinction of the arc.

It will be appreciated that the foregoing examples have been described by way of example only and that the invention can be carried into practice in other ways.

What I claim as my invention and desire to secure by Letters Patent is:

1. An electric circuit-breaker comprising in combination a nozzle of conducting material through which a blast of deionising gas flows to assist in extinguishing the arc, a pair of arc-initiating contacts constituted respectively by a fixed conducting tube disposed substantially in axial alignment with the nozzle on the high pressure side thereof and by a bridging contact member normally connecting such tube with the nozzle but axially movable to break such connection, a fixed arcing contact constituted by a rod disposed within and electrically connected to the tube, a second arcing contact disposed in the low pressure zone with respect to the nozzle, means for separating the arc-initiating contacts and thereby drawing out an arc between them, such arc being transferred by the gas-blast from the arc-initiating contacts to the arcing contacts so

that when so transferred it extends generally centrally through the nozzle, an auxiliary electrode mounted on the low pressure side of the second arcing contact and insulated therefrom, and a resistance through which such auxiliary electrode is connected to the arcing contact rod.

- 5 2. An electric circuit-breaker, comprising in combination two nozzles in axial alignment, means whereby a blast of deionising gas for assisting in extinguishing the arc is caused to flow in two streams directed towards one another respectively through the two nozzles and to discharge outwardly from the low pressure zone between the nozzles, two sets of arc-initiating contacts respectively on the high pressure sides of the two nozzles, means for connecting the two sets of arc-initiating contacts in series with one another, two arcing contacts respectively supported from the high pressure sides of the two nozzles, means for separating the arc-initiating contacts and thereby initially drawing out two arcs in series, such two arcs being transferred by the gas-blast so that they merge into a single arc extending between the two arcing contacts, an auxiliary electrode located in the low pressure zone between the nozzles adjacent to the path of the transferred arc, and a resistance through which such auxiliary electrode is connected to one of the arcing contacts.
- 10 3. An electric circuit-breaker as claimed in claim 2, in which the fixed arc-initiating contact associated with each nozzle is constituted by a rod-like member disposed substantially in axial alignment with the common axis of the nozzles, and the associated arcing contact is constituted by the end of such member.
- 15 4. An electric circuit-breaker as claimed in claim 2, in which the nozzles are made of conducting material insulated from the arcing contacts.
- 20 5. An electric circuit-breaker as claimed in claim 2, in which the two arcing contacts are fixed in position.
- 25 6. An electric circuit-breaker as claimed in claim 2, in which the separating movement of the arc-initiating contacts takes place in a direction transverse to the common axis of the nozzles.
- 30 7. An electric circuit-breaker as claimed in claim 2, in which the separating movement of the arc-initiating contacts is brought about by the pressure of the gas-blast against spring action.
- 35 8. An electric circuit-breaker as claimed in claim 2, in which the nozzles are made of conducting material insulated from the arcing contacts, and the two arcing contacts are each constituted by the end of a rod-like member disposed substantially in axial alignment with the nozzles.
- 40 9. An electric circuit-breaker as claimed in claim 2, in which each set of arc-initiating contacts comprises a fixed contact in the form of a rod-like member disposed substantially in axial alignment with the nozzles, a cooperating moving contact movable transversely to the length of such member, a piston carried by the moving contact and exposed to the pressure of the gas-blast, and a spring normally tending to hold the cooperating contacts in engagement.
- 45 10. An electric circuit-breaker, comprising in combination a restricted vent of conducting material through which a blast of deionising gas flows to assist in extinguishing the arc, at least three contacts associated with the vent of which
- 50 75 two constitute relatively movable arc-initiating

contacts located on the high pressure side of the vent and of which two constitute arcing contacts, one supported from the high pressure side of the vent and the other located in the low pressure zone with respect thereto, yielding means displaceable by the gas-blast for causing the arc-initiating contacts to separate in a direction transverse to the direction of gas flow through the vent and thereby drawing out an arc between them, such arc being transferred by the gas-

10

blast from the arc-initiating contacts to the arcing contacts so that when so transferred it extends generally centrally through the vent, an auxiliary electrode mounted on the low pressure side of the vent, and a resistance through which such auxiliary electrode is connected to the arcing contact supported from the high pressure side, the auxiliary electrode being insulated from the second arcing contact.

DONALD FOSTER AMER.
